UNITED STATES PATENT OFFICE.

OSCAR L. HECKMANN, OF ST. CHARLES, MISSOURI.

FILE HANDLE OR HOLDER.

1,231,884.

Specification of Letters Patent.

Patented July 3, 1917.

Application filed December 29, 1916. Serial No. 139,691.

To all whom it may concern:

Be it known that I, OSCAR L. HECKMANN, a citizen of the United States, residing at St. Charles, in the county of St. Charles, 5 State of Missouri, have invented a new and useful File Handle or Holder; and I do hereby declare the following to be a full, clear, and exact description of the invention, such as will enable others skilled in 10 the art to which it appertains to make and use the same.

This invention relates to an improved file handle or holder, and an object of the invention is to provide an improved device 15 of this kind, having improved means for holding and supporting a flat file.

A further object of the invention is to provide an arched handle having means at one end to receive the tapered shank of the 20 flat file blade, while the other end of the handle engages the edge of the flat file to hold the same against twisting and wabbling.

A further object of the invention is the 25 provision of a screw mounted in one end of the handle and provided with a clamp at one end of said screw having a notch to engage the file to further assist in preventing twisting of the file, said clamp being threaded on the screw so as to be adjusted in different positions, in order to engage different points of the blade of the file. Furthermore, the clamp may engage files of 30 different shapes in cross section.

In practical fields the details of construction may necessitate alterations falling 35 within the scope of what is claimed.

The invention comprises further features and combinations of parts hereinafter set 40 forth, shown in the drawings and claimed.

In the drawings:—

Figure 1 is a view in perspective of the improved file handle or holder constructed in accordance with the invention.

Fig. 2 is a longitudinal sectional view.

Fig. 3 is a cross sectional view on line 3—3 of Fig. 2.

Fig. 4 is a cross sectional view on line 4—4 of Fig. 2.

Fig. 5 is a sectional view on line 5—5 of Fig. 2.

Fig. 6 is a detail perspective view, showing the holder holding its file flatwise.

Referring more especially to the drawings, 55 Fig. 1 designates a handle or holder, which, in

side elevation, is substantially rectangular and arched; therefore, it is provided with a rear downwardly extending arm 2 and a forwardly positioned downwardly extending arm 3. 60

The lower extremity of the arm 2 is provided with a forwardly extending projection 4 provided with a V-shaped slot or recess 5 to receive the tapered shank 6 of 65 the file blade 7.

The file blade 7 is disposed, as shown in the drawings, with one of its edges facing upwardly, so that said edge may be engaged by the lower face of the extremity of the 70 arm 3, to reinforce or brace the file.

The arm 2 is constructed with a threaded opening 8, in which the screw 9 is threaded. The rear end of the screw 9 is formed with a hand-piece 10, whereby the screw 9 may 75 be turned in one direction or the other.

A clamp 11 is threaded on the screw, so as to be moved to different positions thereon and between the arms 2 and 3, so as to prevent wabbling or bending of the file blade 80 (the edge portion of which engages a slot or recess 12 in the clamp 11) between the arms 2 and 3.

If necessary, the clamp 11 may be adjusted to engage the rear face of the lower 85 part of the forward arm 3, so that while the edge of the file blade is in engagement with the slot or recess 12 the file blade is held against wabbling. The clamp 11 is adjusted before the file 7 is arranged in 90 position, for example, should it be desired to adjust the clamp 11 so as to contact with the rear face of the lower part of the arm 3, said screw 9 may be first adjusted so that the threaded reduced part 13 (the threads 95 of which are of the same pitch as the threads of the body of the screw 9) may thread into the recess 14, after which the clamp 11 may be adjusted to engage the near face of the lower part of the forward arm 3, 100 before arranging the file 7 in place. The clamp 11 may be adjusted in any other desired position before inserting the file, and by virtue of this clamp longitudinal movement of the file 7 is prevented, owing to the 105 file being tapering as shown. By means of the threads of the body of the screw 9 and the threads of the reduced part 13 being of the same pitch, the screw may be adjusted, when in the position shown in Fig. 2. 110

The forward extremity of the screw has a reduced part 13 designed to thread into

a recess 14 in the forward arm 3, so that the clamp may be moved to any position along the screw, whereby the slot or recess of the clamp may engage the file blade 5 preventing the same from bending between the arms 2 and 3.

However, a head member or cap 13^a is preferably screwed or threaded on the reduced extension part 13. It is to be noted 10 that by the provision of this head or cap 13^a, the holder may be turned around or disposed in the position shown in Fig. 6, whereby the file or the like may be held flatwise between the end portion of the arm 3 15 and the head member or cap, whereby the file may be held firm, so that the same may be used flatwise on any article to be filed. By this construction, it will be seen there has been produced a device or tool that will 20 perform dual functions. For instance, the head or cap 13^a is adapted to coöperate with the rear face of the lower part of the forward arm 3, in order to steady the screw 9 in position, as shown in Fig. 1. This cap 25 is also adapted to clamp the file flatwise between it and the rear face of the lower part of the forward arm 3, as shown clearly in Fig. 6.

The invention having been set forth, what 30 is claimed as new and useful is:—

1. In a file handle or holder, a frame rectangular and arched in side elevation and

having forward and rear downwardly extending arms having means to engage and hold a file, a screw threaded in one arm, a 35 cap threaded on the extremity of the screw and adapted to clamp a file flatwise against the rear face of one of said arms and also adapted to engage the rear face of one of said arms to steady the screw, and a member 40 threaded on the screw to engage the edge of a file when held edgewise.

2. In a tool holder, a frame rectangular and arched and having forward and rear downwardly extending arms, the extremities 45 of the arms terminating in integral means to engage and hold a file, a screw threaded in the rear arm in parallelism with the arch of said frame and having its forward extremity engaging the rear face of said forward arm for steadyng the screw in position, and a clamp threaded on said screw and designed to be adjusted in various positions and having means to engage the edge of the file when adjusted in any one of the 50 various positions.

In testimony whereof I have signed my name to this specification in the presence of two subscribing witnesses.

OSCAR L. HECKMANN.
